UNITED STATES PATENT OFFICE.

JAMES C. SHEPHERD, OF ST. LOUIS, MISSOURI, ASSIGNOR TO LACLEDE STEEL COMPANY, OF ST. LOUIS, MISSOURI, A CORPORATION OF MISSOURI.

MEANS FOR UNITING CONCRETE REINFORCEMENTS.

Application filed August 12, 1921. Serial No. 491,723.

To all whom it may concern:

Be it known that I, JAMES C. SHEPHERD, a citizen of the United States of America, and a resident of the city of St. Louis and 5 State of Missouri, have invented certain new and useful Improvements in Means for Uniting Concrete Reenforcements, of which the following is a full, clear, and exact description, reference being had to the accompanying drawings, forming a part of this 10 specification.

This invention relates to improvements in means for uniting concrete reenforcements, one of the objects being to provide a simple 15 means whereby reinforcing elements can be easily and quickly assembled to produce a strong reinforcement having its several elements accurately located in predetermined positions. The invention is especially 20 adapted for use in a reinforcing structure having a series of reinforcing elements and a bar, or rod, crossing the several reinforcing elements. For example, a well known type of reinforcement comprises a number 25 of bars located within a long spiral and engaging the inner faces of the coils of the spiral. These coils should be accurately spaced and securely held to prevent accidental displacement of the coils relative to 30 the long bars.

Prior to this invention, the long bars have been placed within the long spiral, and then secured to the coils of the spiral, usually by means of numerous individual attaching 35 devices. These devices are intended to uniformly space the coils and at the same time secure them to the long bars. Obviously, considerable time is required to properly assemble a very large number of individual attaching devices, and this is especially true of the old methods which involve the operations of arranging the long bars within the spiral before the attaching devices are applied to the reinforcement.

45 The new spacing device is preferably provided with a row of open loops adapted to receive the coils of a spiral, so the spacing device can be easily and quickly applied to the spiral. The spacing device also has a row of aligned eyes through which the long bar is inserted, and after the bar has been applied to the spacer, it closes the open loops to confine the coils in said loops. To prevent displacement, a few of the eyes

can be hammered, contracted, or otherwise 55 acted upon to grip the bar.

A further object is to produce a simple spacing device of this kind adapted to be made of inexpensive light wire, and having its elements arranged to effectively prevent 60 accidental displacement of the bar and coils. In the new device the eyes can completely surround the bar, for the bar is merely inserted through the eyes, and the loops which receive the spiral coils can be extended 65 from the eyes so as to offer maximum resistance to any thrusts tending to separate the coils from the bar.

Another object is to produce a long spacing device with rows of eyes and loops 70 adapted to receive different portions of the reinforcement, and having its elements so arranged that accidental breakage of any part of the device will not permit it to fall apart or release it from the reinforcement. 75 This spacing device is preferably a single piece of wire, and if it is accidentally broken at any point throughout its length, it will remain on the reinforcement and continue to perform its functions at all points, excepting the point at which it is broken. 80

A further object is to permit the spiral to be collapsed, or flattened, for shipment as is well understood in this art.

With the foregoing and other objects in view, the invention comprises the novel construction, combination and arrangement of parts hereinafter more specifically described and illustrated in the accompanying drawings wherein is shown the preferred embodiment of the invention. However, it is to be understood that the invention comprehends changes, variations and modifications which come within the scope of the claims hereunto appended. 85 90 95

Fig. I is a horizontal section through a metal reinforcement equipped with a spacing device embodying the features of this invention.

Fig. II is a fragmentary side elevation 100 of the reinforcement.

Fig. III is an enlarged detail view showing a portion of one of the reinforcing bars, and portions of a spacing device whereby coils may be secured to said bar. 105

Fig. IV is a side elevation of the bar and spacing device, the coils being shown in section.

Fig. V is a horizontal section on the line V—V, Fig. III.

To illustrate the invention I have shown spacing devices applied to a metal reinforcement for a concrete column, and this reinforcement includes a reinforcing member A in the form of a long spiral, and bars B arranged longitudinally of the spiral and engaged with the inner faces of the coils 10 of the spiral. These coils are accurately spaced apart and secured to the longitudinal bars through the medium of the spacing devices.

To illustrate this feature of the invention, I have shown a number of long spacers, each comprising a single piece of wire provided with a row of gripping eyes 1 surrounding one of the bars B, and a row of spacing elements 2 uniting said gripping 20 eyes, said row of spacing elements being arranged longitudinally of the bar. Each spacing element 2 may be provided at one of its ends with an abutment loop 3 merging into one of the gripping eyes 1, and 25 a U-shaped loop 4 at its opposite end merging into and extending from another of the gripping eyes.

The coils of the spiral A are located in the U-shaped loops 4, and the open sides 30 of these loops 4 are closed by the longitudinal bars B.

The gripping eyes 1 are preferably in the form of alternating right and left coils, and the abutment loops 3 are extended from the 35 right and left coils to receive a tightening tool whereby said coils may be tightened on the bars B. Fig. V shows a bar B loosely arranged within one of the gripping eyes 1, and it will be apparent that the abutment 40 loop 3 extending from this eye may be hammered in the direction indicated by the arrow, so as to contract the eye 1 on the bar B. Fig. V illustrates the eye 1 and abutment 3 as they appear before the abutment 45 is hammered to contract the eye, and Fig. I illustrates these elements as they appear after the abutments 3 have been hammered to contract the eyes. It is not necessary to hammer, or contract, all of the gripping eyes 1, for the spacer is a long 50 piece of wire provided with a number of eyes 1, all of which are integrally connected together, so if only a few of these eyes grip a bar B, the long spacing device will be securely anchored to prevent slippage of the spacing device on the bar.

It is not difficult to contract the eyes 1 onto the bars B, for this operation can be performed by an ordinary hammer striking 60 the abutments 3. I therefore recommend that many of these eyes be hammered, or otherwise acted upon, to grip the bars B, but these operations should not tend to rotate the spacing device around the bar B 65 on which it is mounted. To avoid this,

the gripping eyes 1 are in the form of right and left coils, as previously pointed out, so even if each abutment 3 is struck by a hammer, the spacing wires will not tend to creep entirely around the bars B. When one of the abutments 3 is struck by a hammer, it will tend to turn that portion of the spacing wire on a bar B, but when the next adjacent abutment 3 is struck by the hammer, the spacing wire will tend to turn in the 75 opposite direction. As a consequence, the hammer blows will not materially displace the spacing devices on the bars.

In each spacing device, the eyes 1 are in alignment with each other, and the loops 4 are also in alignment with each other. The loops 4 extend from one side of the spacing device and the eyes 1 extend from the other side. The loops 4 are open at the side from which the eyes 1 extend (Fig. IV), and each eye 1 is arranged at approximately a right angle to the loops.

In assembling the reinforcement, a long spacing wire is applied to the long spiral A, the coils of the spiral being arranged 90 within the open loops 4 so as to locate the aligned eyes 1 inside of the spiral. After this has been done, a long bar B is inserted through the aligned eyes 1 to confine the coils in the U-shaped loops 4, the open sides of 95 said loops being closed by the bar B, as shown in Fig. IV. Some of the gripping eyes 1 may then be contracted, or otherwise acted upon, to grip the bar B.

Since the bars are merely inserted through 100 the gripping eyes 1 while the reinforcement is being assembled, these eyes can be conveniently made to completely surround a bar B, and this is desirable on account of the strength and stability of an eye entirely 105 surrounding the bar. In the drawings, each eye 1 is in the form of a coil having lapped ends, so as to entirely surround the bar B.

In this new device, the loops 4 which receive the coils of the large spiral A, can 110 merge into and extend directly from the eyes 1 which surround a bar B, and each eye 1 may be provided with a loop 4. By combining the eyes and loops in this manner, each loop 4 cooperates directly with an eye 115 1 to prevent separation of a bar B and the adjacent spiral coils. For instance, refer to Fig. IV and assume that there are stresses tending to force the spiral A away from the bar B. In this event, the spiral A will engage the loops 4 and tend to pull them from the bar B, and displacement of this kind will be most effectively resisted by the eyes 1 which surround the bar B and merge into the loops 4.

Although it is an advantage to use an extremely long spacer made of a single piece of wire, in some cases it is desirable to use several of the spacers on the same bar B, and in this event the spacers can be con- 130

nected to each other as shown at the lower portions of Figs. III and IV. Each spacer is bent at one end to form a hook 6 and a finger 7 extending therefrom, and the opposite end of each spacer is provided with an angular extension 8 adapted to engage a finger 7 and pass through the hook 6 of an adjacent spacer. The adjacent spacers are thus securely interlocked with each other.

This invention is based upon new features not disclosed in an application for patent filed by me on August 19, 1921, Serial No. 493,541, which contains claims broad enough to cover the spacing device herein described.

I claim:

1. In a spacing device adapted to secure longitudinal bars to encircling elements, a spacer comprising a row of gripping eyes alined with each other longitudinally of the spacer and adapted to receive a longitudinal bar, and a row of spacing elements separating said gripping eyes and formed integral therewith, said spacing elements being provided with loops for the reception of said encircling elements, said gripping eyes being in the form of alternating right and left coils and said spacing elements being provided with extended abutment loops to receive a hammer whereby said coils may be tightened on the longitudinal bar.

2. In a spacing device adapted to secure longitudinal bars to encircling elements, a plurality of spacers each comprising a row of gripping eyes alined with each other longitudinally of the spacer and adapted to receive a longitudinal bar, and a row of spacing elements separating said gripping eyes and formed integral therewith, said spacing elements being provided with loops adapted to receive said encircling elements, all of the parts of each spacer being made of a single piece of wire having at one end a hook and a finger extending therefrom, and the opposite end being provided with an angular extension adapted to engage the finger and pass through the hook of an adjacent spacer.

3. In a metal reenforcement for concrete

columns, a reinforcing member in the form 50 of a spiral, a bar arranged longitudinally of said spiral and engaged with the inner faces of the coils of the spiral, and spacers for said coils, each of said spacers comprising a single piece of wire formed with a row 55 of gripping eyes surrounding said bar and a row of spacing elements uniting said gripping eyes, said row of spacing elements being arranged longitudinally of said bar, said gripping eyes being in the form of 60 alternating right and left coils each having at one of its ends a U-shaped loop merging into one of said spacing elements and at its opposite end an extended abutment loop merging into another of said spacing elements, the coils of said spiral being located in the U-shaped loops, and the open sides of 65 said U-shaped loops being closed by said bar.

4. In a metal reenforcement for concrete 70 columns, a reinforcing member in the form of a spiral, bars arranged longitudinally of said spiral and engaged with the inner faces of the coils of the spiral, and spacers for said coils, each of said spacers comprising a single piece of wire formed with a row 75 of gripping eyes surrounding one of said bars and a row of spacing elements uniting said gripping eyes, said row of spacing elements being arranged longitudinally of said 80 bar, each of said spacing elements having at one of its ends an abutment loop merging into one of said gripping eyes and a U-shaped loop at its opposite end merging into and extending from another of the gripping 85 eyes, the coils of said spiral being located in the U-shaped loops and the open sides of said U-shaped loops being closed by said bar, said gripping eyes being in the form of alternating right and left coils and the 90 abutment loops being extended from said right and left coils to receive a tightening tool whereby the right and left coils may be tightened on said bar.

In testimony that I claim the foregoing I 95 hereunto affix my signature.

JAMES C. SHEPHERD.
